OF INDIANA.

SILO-TILE.

1,166,405.

Specification of Letters Patent.

Patented Dec. 28, 1915.

Application filed April 16, 1915. Serial No. 21,845.

To all whom it may concern:

Be it known that we, JOSEPH V. AYER and WILLIAM L. McCAREL, citizens of the United States, residing at Brazil, Clay county, and State of Indiana, have invented and discovered certain new and useful Improvements in Silo-Tiles, of which the following is a specification.

Our invention relates to silo tiles.

- 10 Its object is to provide a tile particularly adapted for use in the construction of silos in which the tile is effectually strengthened in such manner as to resist lateral pressure while at the same time air spaces which are 15 also adapted to perform the function of mortar receiving openings, are provided at such intervals and locations, and of such form as to obtain an effective mortar joint between adjacent tiles.
- 20 With the above object in view our invention is embodied in preferable form in the tile hereinafter described and illustrated in the accompanying drawing.

25 In the drawing the view shown is a perspective end view of the tile.

Referring to the drawing, the tile is preferably constructed of clay and has two large openings 1 and 2 extending longitudinally of the tile as is usual in such construction. 30 These openings leave an upper horizontal cross wall 3, a lower horizontal wall 4, a central cross web 5 and two vertical side walls 6 and 7. The upper opening has an inner upper flat face 8 parallel with the upper outer face 9 of the tile, and vertical side faces 10 parallel with the outer vertical plane face of the side wall of the tile. The horizontal inner faces of the top and bottom walls and the side faces 10 are joined by 35 inclined or angular corner faces 12, leaving a comparatively wide space between each face 12 and the opposing portion of the outer face of the side wall of the tile. The inner corners of the opening 1 are joined by 40 shorter angular faces 13. The lower opening 2 is formed similarly to the upper opening 1 with wide angled outer corners and shorter angled inner corners.

45 In each side wall of the tile is formed a series of longitudinally extending apertures providing dead air spaces preferably five in number. The upper and lower spaces 14 of each of these series are constructed alike and 50 each has a vertical face 15 parallel with the vertical side surface of the tile, a horizontal

outer face 16 parallel with the horizontal faces of the tile and an angular face 17 which is parallel with the inclined face 12 of the adjoining large opening 1 or 2, and which inclined face is spaced from said face 12. The outer face of the triangular air spaces 14 thus formed, is preferably on a line with the horizontal faces 8 of the central openings and the inner terminations of said openings 14 are preferably on a line with the inner corners of the inclined faces 12.

55 Between the spaces 14 in the side webs of the tile are formed longitudinal apertures forming air spaces 18 substantially opposite the central portion of the large openings 1 and 2 respectively. These spaces have outer vertical side faces 19 and inner side faces 20 which are longer than the outer faces 19, and said side faces are joined by 60 angular end faces 21 which are in continuation of the lines of the corners 12 and 13 of the large central openings.

65 Between the spaces 18 in each side wall of the tile and opposite the central cross web 5 is formed a longitudinal air space 22 of triangular form and having a vertical side face 23 and two inclined faces 24, which extend inwardly and which are parallel to the lines of the corners 13 of the central openings and the end faces 21 of the openings 18.

70 By the above construction and arrangement of the central openings and lateral air spaces, angularly formed web portions will be provided in the side walls of the tile as indicated by the numerals 25, 26, 27 and 28. Such angular formation of the side walls leaves wide areas between adjacent openings and strengthens the tile and resists lateral pressure from the adjoining tiles which is a feature of great importance in silo construction. The angular ends of the spaces 18 and the angular corners 13 of the central openings in conjunction with the inner inclined faces 24 of the openings 22, 75 enable these latter openings to be placed opposite the central cross web without impairing the strength of the walls of the tile at this point and thus permit a sufficient number of openings to be formed in the vertical side walls to obtain a mortar joint of effective length.

80 Mortar is adapted to be placed along the end edges of the air spaces in the side walls and when two tiles are placed together end 85

to end, the mortar will be forced slightly within these openings, thus locking the tiles firmly together. The outer line of the walls of these air spaces forms a straight vertical line but the inner edges owing to the inclined walls 17 and 24 of the triangular air spaces form a broken line, and the inclinations of said walls being between a vertical and a horizontal line, tend to resist both vertical and lateral stress, and thus aid in more effectually maintaining the mortar joint intact.

Having thus described our invention what we claim is:

15. 1. A tile having side walls provided with continuous vertical plane outer faces and parallel inner faces and having top and bottom walls with horizontal parallel inner and outer faces, said tile having angled inner corner surfaces joining said inner vertical and horizontal faces, said walls having longitudinal apertures in the corners thereof, the surfaces of which are parallel respectively to the inner vertical, horizontal and 25 corner faces of the tile.
2. A tile having a large longitudinal opening and having top and bottom horizontal walls and vertical side walls, said walls having in the corners thereof longitudinal apertures with vertical and horizontal faces and with an inclined face joining the vertical and horizontal faces and said vertical side walls having a plurality of longitudinal apertures therein between said corner 30 apertures, said intermediate apertures having the faces thereof which extend from the outside inwardly inclined to the horizontal, the adjacent faces of adjoining openings being parallel, whereby angularly extending 35 40 web portions in the side walls are provided.

3. A hollow tile having large central longitudinal openings therein, a central cross web spacing said openings apart, said tile having angular faces at the inner corners of each of said openings, the side walls of the 45 tile having longitudinal air space apertures opposite said central web, each of said openings having a vertical outer face and inclined inwardly extending faces respectively parallel to the angular corner faces of the 50 upper and lower large central openings.

4. A hollow tile having large central longitudinal openings spaced apart vertically leaving a central cross web and having angular inner and outer faces at the corners of said 55 openings, the outer corner faces being longer than the inner faces, said tile having a series of angled air spaces in each side wall of the tile comprising upper and lower spaces each having a face parallel to the outer angular corner face of the adjacent large openings, which side wall having an air space opposite the central cross web which has inwardly extending faces respectively parallel to the inner corner faces of the upper and 60 lower central openings, and air spaces between the end spaces and said middle space having inwardly extending angular faces respectively parallel to the adjacent faces of the spaces above and below it.

In witness whereof, we have hereunto set our hands and seals at Brazil, Clay county, Indiana, this 10th day of April, A. D. nineteen hundred and fifteen.

JOSEPH V. AYER. [L. S.]
WILLIAM L. McCAREL. [L. S.]
